APPLICATOR BANDAGE FOR TOPS OF POLES
Robert M. Reddin and Robert E. Branch, Memphis, Tenn.,
assignors to Chapman Chemical Company, Memphis,
Tenn., a corporation of Illinois

Filed June 2, 1961, Ser. No. 114,548
6 Claims. (Cl. 206—65)

The present invention relates to an improved wood pole treating bandage for supporting and enclosing a wood preservative-protective grease product to be applied to the top of a line pole.

The invention pertains to the method of treating wood with preservative-protective material after the wood is put in use, and particularly to treating wood posts or poles such as electrical line poles. The poles are treated by applying wood preservative to the top end where it can penetrate the end grain of the wood. This extends the useful life of poles already in the line by adding extra years of service and the application of preservative will add extra years to the life of the poles. Poles which were poorly treated upon installation or were not treated, or were treated with inferior preservatives can be treated with materials of an improved character. The preservative material is a grease or a grease-like composition which is carried on a bandage forming a protective enclosure during storage and handling and forming an applicator and carrier for applying to the pole. The bandage is particularly adapted to being suspended on an applicator tool which is elevated to the top of a pole for applying the bandage.

A feature of the invention is the provision of a bandage construction having a supporting layer of water soluble film for dissolving when exposed to precipitation with a slab of wood preservative-protective grease material on the layer, and with a layer of porous material such as crinoline over the grease material and a further removable protective layer of water soluble film secured by a continuous seam at its edges to the supporting layer and positioned over the porous layer and readily separable therefrom for removal in order that the grease material may be placed over the top of a pole with the porous material facing downwardly.

A further feature of the invention is the provision of an improved method and machine for the construction of the wood pole treating bandage, by supporting a layer of water soluble film and placing a walled open template on the film, filling the template with a wood preservative grease and removing the template, placing a porous layer of material over the grease and placing a layer of protective film over the porous material and forming a seam between the outer layers around the grease.

Accordingly, an object of the present invention is to provide an improved wood preservative grease bandage for mounting on an applicator to apply to the top of a line pole.

A further object of the invention is to provide an improved wood treatment bandage of simplified construction well adapted for use in the field for protecting the grease product, and for ease of opening and attachment to an applicator and adapted for convenient handling and application to the top of a line pole.

A further object of the invention is to provide an improved method and mechanism for manufacturing bandages of the type described, wherein the bandages can be quickly and easily made without contact by the operator with the preservative grease product.

A still further object of the invention is to provide an improved wood treatment bandage construction and package therefor for storing and handling.

An overall object of the invention is an improvement in the art of applying a material to the top of standing

2

poles and to poles prior to installation which will provide long term weather protection as well as a wood preservative treatment, and relates to an improvement in the application of the material and to the form in which it is produced, packaged, handled and applied.

An object is to produce a satisfactory bandage which accommodates the varying shapes and sizes of the tops of poles, the sticky and very solvent nature of such compounds which give satisfactory preservation and protection, and which provides an end product that is safe and attractive.

Other objects and advantages will become more apparent with the teaching of the principles of the invention in connection with the disclosure of the preferred embodiments thereof in the specification, claims and drawings, in which:

FIGURE 1 is a perspective view of a wood preservative grease bandage constructed in accordance with the principles of the present invention;

FIGURE 2 is a vertical sectional view taken substantially along line II—II of FIGURE 1;

FIGURE 3 is a perspective view of another form of grease bandage constructed in accordance with the principles of the invention;

FIGURE 4 is a vertical sectional view illustrating the manner in which the bandage is applied to a pole top;

FIGURE 5 is a vertical sectional view illustrating a step in the manufacture of a bandage;

FIGURE 6 is another vertical sectional view illustrating a further step in the manufacture of the bandage;

FIGURE 7 is a vertical sectional view illustrating a modification of a step in the manufacture of the bandage;

FIGURE 8 is a top plan view of a mechanism for performing the method of the invention and making the bandage, constructed in accordance with the principles of the invention;

FIGURE 9 is a side elevational view of the mechanism of FIGURE 8;

FIGURE 10 is a vertical sectional view taken through a container for storing and shipping the bandage;

FIGURE 11 is a fragmentary vertical sectional view taken substantially along line XI—XI of FIGURE 10; and

FIGURE 12 is a fragmentary vertical sectional view illustrating a further way of packaging bandages.

As shown on the drawings:

As illustrated in FIGURES 1, 2 and 4, the bandage 14 has a first support film 15 of water soluble material. For example a two mil thick polyvinyl alcohol cold water soluble film is well suited. On the support film 15 is placed a circular slab or deposit of wood preservative grease 16 such as a pentachlorophenol based grease. A preservative-protective material such as that described in U.S. Patent 2,904,467 Behr, is well suited.

Over the grease 16 is placed a layer of porous material 17 such as crinoline. The layer acts as a separator permitting easy separation and removal of an upper protective film 18 which is later cut from the bandage along the line 20 and the center portion stripped off so that the grease preservative product 16 can penetrate the crinoline 17 and penetrate the pole top to which it is applied. The crinoline is shown as a rectangular patch in FIGURE 1, extending past the grease 16 at its ends. This permits an applicator to clamp the ends of the crinoline, FIGURE 4, and hold the pad of grease in position. The protective layer of film 18 is preferably of the same composition as the support layer 15, being of a water soluble film, so that its edges, which are left on the bandage when the center of the film 18 is removed, will dissolve when exposed to weather and precipitation. The lower and upper layers 15 and 18 of film are joined

by a continuous seam 19 and the film is preferably a thermoplastic material so that a heat seal can be used. This will provide a closed package preventing bleeding out of the grease or the escape of odors and fumes.

For use and application to the top of a pole, the protective layer 18 is cut such as by a knife or razor blade along the line indicated at 20 so that the center portion can be stripped off to expose the crinoline layer. The bandage is then applied to a pole top, and may be handled by an applicator such as shown in FIGURE 4 having a pair of clamping rings 22 and 23 which engage and clamp the edge of the bandage therebetween. The rings engage the ends of the crinoline 17, to hold the pad of grease in position. The clamping rings are separated to release the bandage when the bandage is in place at the top of a pole 21, as shown in FIGURE 4, and the grease will protect the pole top and will penetrate the wood while the remaining film will dissolve.

A form of bandage 24 is shown in FIGURE 3, specifically adapted to use by an applicator tool that has projecting prongs thereon for horizontally suspending the bandage. In the bandage 24, the construction is substantially the same as the bandage 14 of FIGURES 1 and 2, but a series of holes 25 are arranged annularly at the edge of the bandage and outside of the center enclosed grease deposit 26. Projections on an applicator tool extend through the holes to suspend the bandage horizontally. The bandage is shown preferably as circular in shape although a rectangular form may be used, with the openings 25 outside of a seam 27 which joins the layers, so that the compartment that contains the grease remains sealed.

FIGURES 5 and 6 illustrate steps in the method of making the bandage. A support table or surface 28 supports a lower support film or layer 29 and a template 30 is positioned on the film 29. The template has an annular upwardly extending wall 31 to define an opening in which is placed a circular slab 32 of wood preservative grease. The grease may be applied in any suitable manner such as by a trowel and smoothed to the level of the template.

As an example, the finished bandage may be square, or oblong which effects a saving in film material. The template may be made of wood or metal and may be, for example, $\frac{3}{4}$ of an inch in depth containing a circular opening 14" in diameter, and these proportions are well suited for making a package for applying to the top of a line pole. It of course is to be understood that these sizes are given by way of example and are not limiting since a large range of sizes may be used. The template 30 is then removed and a porous separating layer 33 is applied over the grease and an outer film layer 34 is applied over the porous layer 33. The film 34 is sealed to the film 29 such as by a heat sealing tool 35 which forms a seam 36 around the grease slab 32. If a plurality of bandages are made from extended sheets of film, the bandages can be separated from each other by cutting such as illustrated at 37 between the seam 36 and another seam 38 formed for an adjacent bandage.

FIGURE 7 illustrates another method of forming a bandage wherein a support surface 39 is provided for a support film 40 and a template 41 having an annular wall forming an opening therein, as placed on a support film 40. Within the template opening is placed a liner sheet or film 42 which also preferably is made of a water soluble material. A layer of wood preservative-protective grease 43 is filled in the liner film 42 within the template 41 to the level of the template and a layer of porous material 44 is placed over the grease. The porous material 44, such as crinoline, may be placed over the grease either before the template is lifted or after and is preferably substantially the size of the grease layer although it can extend over its edges. If the porous layer 44 is placed over the grease after the template

is raised, the possibility of the layer 44 being lifted with the template is avoided.

FIGURES 8 and 9 show a machine for performing the method and making the package of the invention, including a table 45 with a support table top 46. Brackets 47 at one end of the table support a film supplying roll 48 conveniently positioned for drawing layers of film over the top of the support table top surface 46. The lower support layer can be first drawn over the table top, and cut along its supply edge and another outer protective layer drawn over the table top after the slabs of grease are in place with the patches of porous material over each slab.

Hingedly mounted at the end of the table top is a multiple opening template 49 which pivots down over a support sheet in the position shown in FIGURE 8 and pivots upwardly out of the way to the position shown in FIGURE 9 after the grease slabs have been deposited. When the slabs have been deposited by filling in the openings 50 in the template 49, the template is pivoted upwardly to the position of FIGURE 9, patches of crinoline are placed over each of the slabs of grease, and an upper layer is drawn from the roll 48 over the slabs. Heat seals are formed surrounding each of the slabs by sliding heat sealed bars 52 and 53. The bar 52 is slidably mounted on a rail 51 at one side of the table so as to move along and form cross seals between the slabs. Similarly, the bar 54 is slidable on a rail 53 on an adjacent side of the table and forms seams along between the slabs and outwardly thereof. The seams are formed in double rows as indicated schematically in FIGURE 8 by the seam lines 52a and 54a and the material is cut between the seam lines to complete the packages.

FIGURES 10 and 11 and FIGURE 12 illustrate ways in which the bandage is packaged for shipping, with FIGURE 12 illustrating an advantageous way of shipping multiple bandages. In FIGURES 10 and 11, a bandage 56 is placed in a container 55 which may be of fiberboard or a similar material and may be circular in shape or rectangular. Surrounding the central grease deposit 56a in the package 56, is placed an annular cardboard ring 57, and a circular cardboard disk 58 is placed over the top of the grease deposit. The ends 59 and 60 of the package are then swung upwardly over the disk 58 and the package placed in the container which is then closed. The looping upwardly of the ends of the package helps hold the package firmly and the grease deposit is prevented from oozing and bleeding outwardly to the seams of the bandage and a natural buffered support is provided. As shown in FIGURE 12, fiber drums are used with a drum 61 containing bandages 62 each situated within separating collars or rings 63 and separated from each other by disk spacers 64.

In brief summary, the bandage, as shown in FIGURES 1, 2 and 4 incorporates a support layer of water soluble thermoplastic film 15 upon which is deposited a circular slab of wood preservative-protective grease 16, covered by a layer of porous material such as crinoline 17. An upper protective layer 18 extends over the crinoline and is seamed to the lower layer at a seamed edge 19. For application to the top of a utility pole, as shown in FIGURE 4, the upper protective layer is cut at 20 and stripped from the crinoline and the bandage is inverted and applied to the top of the pole 21.

Thus it will be seen that we have provided an improved bandage and method and mechanism for making the bandage for use with an applicator tool to be applied to the top of a pole. The bandage is reliable and protects the preservative material during storage and handling, and is well adapted for use with an applicator tool. A bandage is provided, which accommodates itself to varying shapes and sizes of tops of poles and to the sticky and solvent nature of compounds used for preservative and protection, and yet provides a safe and attractive means for storing and handling the material.

The drawings and specification present a detailed disclosure of the preferred embodiments of the invention, and it is to be understood that the invention is not limited to the specific forms disclosed, but covers all modifications, changes and alternative constructions and methods falling within the scope of the principles taught by the invention.

We claim as our invention:

1. A wood pole treating bandage construction comprising a supporting layer of water soluble film for dissolving when exposed to precipitation, a deposit of wood preservative-protective grease material on said layer, a layer of porous material over said grease material, a removable protective layer of water soluble film secured at its edges to said supporting layer and positioned over said porous layer and readily separable therefrom for placing the grease material over the top of a pole with the porous material facing downwardly, and means defining a series of annularly arranged spaced openings through said film layers radially outside of the location where the layers are secured for the insertion of supporting members for suspending the bandage for applying to the top of a pole.

2. A packaged wood preservative-protective bandage comprising in combination a bandage structure having upper and lower layers of film with a circular deposit of wood preservative grease sealed therebetween, an annular stiffening ring resting on the layers of film and surrounding the grease, a circular disc placed over the grease, with the ends of the bandage being folded upwardly over the disk, and an outer protective container surrounding the bandage and its ring and disk.

3. A packaged wood preservative-protective bandage comprising in combination a bandage structure having upper and lower layers of film with a substantially circular deposit of wood preservative grease sealed therebetween, a cylindrical container for receiving the bandage structure, an annular stiffening ring within the container surrounding the grease and protecting it in a radial direction, and a circular disk placed over the grease supported on the ring for protecting the grease in an axial direction and supporting additional bandage structures, said upper and lower layers of film being folded upwardly over the outer surface of the disk.

4. A wood pole treating bandage construction comprising a supporting layer of water soluble thermoplastic film for dissolving when exposed to precipitation, a slab of wood preservative-protective grease material on said layer, a layer of a permeable separation material over said grease material, and a protective layer of water soluble thermoplastic film positioned over said permeable layer and readily separable therefrom for removing the center portion of said protective layer for placing the grease material over the top of a pole with the permeable material facing downwardly, said film layers having a heat seal

joining the layers to each other around the edges radially outwardly of the grease material for enclosing the grease material with the edge of the protective layer and the heat seal remaining on the pole with the supporting layer.

5. A wood pole treating bandage construction comprising a supporting layer of water soluble film for dissolving when exposed to precipitation, a circular shaped deposit of wood preservative-protective grease material at the center of said layer, a layer of porous material over said grease material, and a protective layer of water soluble film positioned over said porous layer and readily separable therefrom for removing the center portion of said protective layer for placing the grease material over the top of a pole with the porous material facing downwardly with the edge of the protective layer and the supporting layer remaining on the pole, said film layers being sealed to each other in face to face relationship outwardly of the grease deposit presenting a flange for gripping the bandage radially outwardly of the grease material.
- 10 6. A wood pole treating bandage construction comprising a supporting layer of water soluble film for dissolving when exposed to precipitation, a slab of wood preservative-protective grease material on said layer, a layer of crinoline placed over said grease material, and a protective layer of water soluble film secured at its edges to the supporting layer radially outwardly of the grease material providing a gripping flange and positioned over said layer of crinoline and readily separable therefrom for removing the center portion of said protective layer for placing the grease material over a pole with the crinoline facing downwardly with the edge of the protective layer and the supporting layer remaining on the pole.
